UNITED STATES PATENT OFFICE.

HEZEKIAH A. BENSON, OF BRIDGEPORT, CONNECTICUT.

ROTARY ENGINE.

SPECIFICATION forming part of Letters Patent No. 679,936, dated August 6, 1901.

Application filed October 5, 1900. Serial No. 32,138. (No model.)

To all whom it may concern:

Be it known that I, HEZEKIAH A. BENSON, a citizen of the United States, residing at Bridgeport, in the county of Fairfield, State of Connecticut, have invented a new and useful ⁵ Rotary Engine, of which the following is a specification.

My invention has for its object to generally simplify and improve the construction of this ¹⁰ class of engines, my novel engine being very compact and very powerful, light in weight, and inexpensive to build, easily reversible, adapted to stop and start anywhere, there being no dead-point, there being practically no ¹⁵ wear or friction, as the motion of every part without exception is rotary, and, most important of all, back pressure being wholly prevented. In order to accomplish these results, I have devised an engine which I will now ²⁰ describe, referring to the accompanying drawings, forming part of this specification, and using reference characters to designate the several parts.

Figure 1 is a front elevation of my novel engine, the controlling-lever being in the stationary position; Fig. 2, a corresponding rear elevation; Fig. 3, a side elevation as seen from the left in Fig. 1 and from the right in Fig. 2; Fig. 4, a horizontal section on the line ²⁵ 4 4, the parts being stationary; Fig. 4^a, a detail sectional view of one of the auxiliary valves and the corresponding sleeve on the line 4^a 4^a in Fig. 4; Fig. 5, a detail sectional view on the line 5 5 in Figs. 3 and 4; Fig. 6, ³⁰ a vertical section on the line 6 6 in Figs. 3 and 4, showing one piston and the corresponding auxiliary disk in the stationary position; Fig. 7, a similar view showing the piston and the auxiliary disk in the operative position ³⁵ and moving forward; Fig. 8, a detail sectional view corresponding with Fig. 5, but showing in full lines the main valve in position to produce forward movement and in dotted lines the main valve in position to produce reverse ⁴⁰ movement; and Fig. 9 is a detail sectional view on the line 9 9 in Fig. 4, the position of the parts, however, corresponding with Fig. 7.

The body of the engine may of course be made in any preferred manner. I have illustrated a body comprising a central casting A and two end castings, (indicated, respectively, by B and C,) said castings being secured to-

gether by bolts 76. Within the body are cylinders—for example, two, three, or even more ⁵⁵ cylinder—and corresponding pistons and auxiliary parts. In the present instance I have shown an engine embodying two cylinders and pistons and the corresponding auxiliary parts, the cylinders being designated, respectively, by 20 and 21.

22 and 23 denote auxiliary cylindrical chambers contiguous to the cylinders. Each cylinder and the corresponding auxiliary chamber communicate by means of an opening 24, and each cylinder and its corresponding auxiliary chamber are separated from the other cylinder and its corresponding auxiliary chamber by means of a wall or plate 25, which may be made in one or more parts, as preferred, and may be secured in place in any ⁶⁵ 7c suitable manner. In the present instance I have shown wall 25 as comprising two plates, each having a straight side engaging the other plate, as at 26, (see dotted lines, Figs. 6 and 7,) for convenience in retaining the plates in ⁷⁵ place.

27 and 28 denote pistons in cylinders 20 and 21, respectively. The pistons are of less diameter than the cylinders, but each piston is provided with a radial float or sweep 29, which ⁸⁰ as the piston revolves closely engages the inner periphery of the cylinder, the floats being shown as placed opposite to each other. The pistons are rigidly secured to a driving-shaft D, the inner end of said shaft (see dotted lines, Fig. 4) being shown as stepped in casting B, said shaft extending outward through wall 25 and casting C and through a stuffing-box 30, which is bolted to casting C.

31 and 32 denote auxiliary disks in auxiliary chambers 22 and 23, respectively. The auxiliary disks are of the same diameter as the pistons, fit closely in the auxiliary chambers, and extend through openings 24 and engage the peripheries of the pistons closely, ⁹⁰ thereby preventing back passage of steam, as will be more fully explained. Each auxiliary disk is provided in its periphery with a recess 33, which is of suitable size to receive the corresponding float 29 and give clearance ⁹⁵ thereto, but which will not permit the passage of steam between the piston and the auxiliary disk.

34 denotes an auxiliary shaft, to which the

auxiliary disks are rigidly secured. This shaft may be stepped in casting B (not shown in the drawings) and passes outward through wall 25 and casting C and through a stuffing-box 30, which is bolted to casting C. Motion is communicated from the driving-shaft to the auxiliary shaft by means of a gear-wheel 67 on the driving-shaft, which meshes with a corresponding gear-wheel 68 on the auxiliary shaft.

38 denotes a steam-pipe, and 39 an exhaust-pipe, which are shown as connected to a steam-chest E. Within the steam-chest is a steam-port 40, leading to a central opening 41, within which is the main valve 42.

43 and 44 denote ports leading from opening 41 to openings 45 and 46, respectively. Within openings 45 and 46, which are shown as extending through castings A and B and into casting C, are auxiliary valves, (denoted, respectively, by 47 and 48,) and outside of the auxiliary valves and closely filling the openings are oscillatory sleeves 49 and 50, the functions of which will presently be fully explained.

51 denotes an exhaust-port leading from central opening 41, intermediate ports 43 and 44. The main valve is carried by a shaft 52, which extends outward from casting B through a stuffing-box 53 and carries the controlling-lever 54. Auxiliary valves 47 and 48 are carried, respectively, by shafts 62 and 63, which extend outward through hubs 64 on casting C and carry at their outer ends gear-wheels 65, both of which mesh with a gear-wheel 66 of uniform size therewith on driving-shaft D, whereby motion is communicated from the driving-shaft to shafts 62 and 63 and the auxiliary valves are caused to rotate in time with the pistons, but in the opposite direction. Shaft D also carries another gear-wheel 67, which meshes with a gear-wheel 68 on auxiliary shaft 34, whereby motion is communicated from the driving-shaft 45 to the auxiliary shaft and the auxiliary disks are caused to rotate in time with the pistons, but in the opposite direction.

The main valve is an ordinary two-way valve. Its construction will be readily understood from Figs. 4, 5, and 8. In the position shown in Figs. 4 and 5 this valve cuts off the passage of steam into the steam-chest, and the engine consequently remains stationary. In the position shown in full lines in Fig. 8 the controlling-lever has been moved to the position indicated by dotted lines in Fig. 7, which places the main valve in a position to permit steam to pass through port 44 to auxiliary opening 46 and through auxiliary valve 48 to the cylinder, the position of the auxiliary valves and the corresponding sleeves when the engine is taking steam for forward movement being clearly shown in Fig. 7. The dotted position of the main valve in Fig. 8 is 65 the position of said valve when taking steam for reverse movement. The construction of the auxiliary valves and the sleeves will be

readily understood from Figs. 4, 4^a, 5, and 6. The auxiliary valves are in fact cylinders closed at both ends. Each valve is provided with a circumferential groove 70, which registers with the port from the main valve and with holes 71, leading from the groove into the interior thereof. Each auxiliary valve is also provided with a port 72, adapted to register with a port 73 in the body, which leads into cylinder 20, and with a port 74, adapted to register with a port 75 in the body which leads into cylinder 21. As shown in Fig. 4, the ports 72 and 74 are out of alignment with each other, so that steam passes alternately through them. It will be noted in Fig. 4 that ports 72 and 74 in the auxiliary valves extend in length the entire width of the cylinders, and in Figs. 6 and 7 that in the engine illustrated, which is a two-cylinder engine, these ports have a width approximately one-fourth the circumference of the valves themselves. In a three-cylinder engine the auxiliary valves would of course be longer and would 90 be provided with a port for each cylinder, and each port would have a width approximately one-sixth of the circumference of the valve. In a four-cylinder engine the auxiliary valves would have four ports, and said ports would 95 have a width approximately one-eighth of the circumference of the valves. I have not referred to a one-cylinder engine, although the principle of my invention is perfectly applicable to a one-cylinder engine having a fly-wheel. In a one-cylinder engine the width of the ports in the auxiliary valves would be approximately half the circumference of the valves themselves. Sleeves 49 and 50 completely fill the respective openings 45 and 46, 105 said sleeves being adapted to oscillate within the openings and the auxiliary valves to rotate within the sleeves. Each sleeve is provided with an opening *d*, which is made large enough so that no matter what position the 110 sleeves may be in ports 43 and 44 in the steam-chest will never be closed thereby, so that whenever steam passes the main valve it is also free to pass into one of the auxiliary valves. Each sleeve is also provided with relatively 115 small openings *h* and relatively large openings *k*. The solid metal of the sleeves between the corresponding openings *h* and *k* I have for convenience indicated by *g*. It should be understood that one of the openings *h* and the corresponding opening *k* in each sleeve correspond to the port 73 for cylinder 20, and the other opening *h* and corresponding opening *k* in each sleeve correspond to the port 74 for cylinder 21. It will be obvious from the description already given that the auxiliary valves and the sleeves correspond in length with the length of the space occupied by the cylinders and the separating-walls, the openings in the auxiliary valves and the sleeves corresponding with the number of cylinders and pistons. In practice openings *h* and *k* are made the full length of the corresponding ports, and openings *h* have a width approxi-

mately one-fourth the circumference of the sleeves. Sleeves 49 and 50 are carried, respectively, by shafts 55 and 56, which extend outward through hubs 69 on casting B and through stuffing-boxes 53 and carry in the present instance at their outer ends pinions 57. Shafts 52, 55, and 56 and with them the main valve and sleeves 49 and 50 are operated together by means of the controlling-lever, any suitable connections being provided between shaft 52 or the controlling-lever and the auxiliary shafts. In the present instance I have shown the auxiliary shafts as operated by means of racks 58, 15 which are pivoted to the controlling-lever and engage pinions 57, a spring 59 acting to retain the racks in the engaging position. As a means of retaining the controlling-lever in the intermediate or inoperative or in 20 either of its operative positions I have shown the lower end of said lever as made in the form of a segment and provided with notches 60, either of which is adapted to be engaged by a spring-catch 61.

25 The operation is as follows: Starting with the parts in the stationary position, as in Figs. 1 to 6, inclusive, if it is desired that the engine turn forward the controlling-lever is moved toward the right to the position shown 30 in dotted lines in Fig. 7, in which position it is locked by the engagement of spring-catch 61 with the right notch 60, as seen in Fig. 1, in the segment at the lower end of said lever. This movement of the controlling-lever 35 places the main valve in the position shown in Fig. 8 and the sleeves in the position shown in Fig. 7. Steam now passes through port 44 to auxiliary valve 48, thence through port 73 to cylinder 20, in which it acts upon the float 29 of piston 27 and causes said piston and the driving-shaft to rotate. It will be noted that 40 the steam acting upon the floats develops great power owing to the long leverage, the entire action of the steam owing to the disk 45 shape of the piston itself being at a distance from the pivotal point of the piston. As soon as the piston has been carried around far enough, so that the float will have passed the port 73 on the opposite side of the cylinder 50 which leads to the other auxiliary valve, the steam will pass through the other auxiliary valve, in this instance valve 47, thence through port 43 (see Fig. 8) and central opening 41 to the exhaust-port. Should it be desired 55 to reverse the engine, the controlling-lever is moved past the inoperative position shown in full lines toward the left, as seen in Fig. 1, the effect of which is to place the main valve in the position indicated by dotted lines in Fig. 8 and to reverse the positions of the sleeves from those shown in Fig. 7—that is to say, when the engine is reversing—i. e., when the pistons are turning backward sleeve 49 will be in the position in which sleeve 50 is shown in Fig. 7 and sleeve 50 will be in the position in which sleeve 49 is shown in said figure, and the pistons instead of mov-

ing in the direction of the arrow in Fig. 7 will move in the reverse direction, steam now entering the cylinder through port 43 and the 70 exhaust now being through auxiliary valve 48, port 44, and the central opening to the exhaust-port.

For the sake of clearness in description I have made no reference in the last paragraph 75 to the entrance of steam into cylinder 21. In Fig. 9, however, I have shown the position of auxiliary valve 48 and its port 74, which corresponds with cylinder 21 at the instant port 72, corresponding with cylinder 20, is in the 80 position shown in Fig. 7, these ports being of course diametrically opposite to each other, as are the floats upon the pistons. It will be noted in Figs. 6 and 7 that the position of ports 73 in the body is such that the steam is 85 acting upon both floats a portion of the time and that there is no instant of time that steam is not acting upon one of the floats, so that the possibility of a "dead-point," so called, is eliminated from the engine. 90

In order that my novel engine and its operation may be clearly understood, I will now trace the passage of steam from steam-port 40 back through the central opening to exhaust-port 51 when the engine is moving forward and will explain the movements of the parts. The main valve being in the position shown in full lines in Fig. 8, steam passes into opening 46, and thence through opening *d* in sleeve 50 and holes 71 into auxiliary 100 valve 48, it being understood that the openings *d* in both of the sleeves are large enough, so that steam will pass freely into the auxiliary valves at all times, there being no position of the sleeves that will cut off the passage 105 of steam into the auxiliary valves. Turning now to Fig. 7, steam will pass freely through port 72 in auxiliary valve 48, opening *h* in sleeve 50, and the left port 73 into cylinder 20. In this cylinder the passage of steam in 110 one direction will be cut off through the close engagement of auxiliary disk 31 with piston 27, so that the entire power of the steam will be exerted upon the float 29 of piston 27 and will turn said piston in the direction 115 of the arrow. As soon as the float has made a half-revolution from the left port 73 steam will begin to enter cylinder 21 through the other port 74 in auxiliary valve 48 and the corresponding opening *h* in the sleeve, said 120 port 74 being now at the position in which port 72 is shown in Fig. 7, bearing in mind, however, that when port 72 is in the position shown in Fig. 7 port 74 is in the position shown in Fig. 9. As already stated, after the 125 float in cylinder 20 has made a half-revolution from the point at which the steam commenced to act thereon steam will commence to act upon the other float 29 in cylinder 21, both floats being thus acted upon by steam 130 until the float in cylinder 20 passes the right port 73. The instant the float in cylinder 20 has passed this port the steam will exhaust through said port into opening *k* in sleeve 49

and through port 72 in auxiliary valve 47, thence outward through holes 71 and opening *d* into port 43, and thence through the main valve to exhaust-port 51. After the steam has commenced to exhaust from cylinder 20 steam will continue to act on the float in cylinder 21, the action of the steam in cylinder 21 not ceasing until after it has commenced to act again on the float in cylinder 20. It should be noted that the relation between floats 29 and recesses 33 in the auxiliary disks is of vital importance. These recesses are provided to give perfect clearance for the floats. While the floats are passing through the recesses— in fact, after the float has passed the port 73, that is acting as an exhaust-port—there will be no action of steam upon that float, and, furthermore, prior to this, as will presently be fully explained, the steam will have been cut off from that cylinder, the action of the steam upon each float during a portion of each revolution being expansive. It will be understood, therefore, that while a float is passing through one of the recesses 33 in an auxiliary disk the steam is wholly cut off from said cylinder, so that there can be no back pressure, and that at all other times back pressure is wholly prevented through the contact of the cylinder with the corresponding auxiliary disk. In order that it may be perfectly clear why steam that has passed the main valve can always pass through an opening *d* in one of the sleeves and into the corresponding auxiliary valve, but can only pass into the corresponding cylinder when the float therein has reached a position that makes back pressure impossible, I have illustrated in Fig. 9 the position of port 74 in auxiliary valve 48 at the instant port 72 in said valve is delivering steam to cylinder 20. It will be obvious from Figs. 7 and 9 in connection with Fig. 4 that steam passing port 72 continues through opening *k* and port 73 into cylinder 20 and from Fig. 9 that steam passing port 74 can pass no farther, but is retained by the walls *g* of opening *k* of the sleeve. It will be remembered that the auxiliary valves, the pistons, and the auxiliary disks rotate in unison with each other. Turning again to Figs. 6 and 7, it will be apparent that steam is acting upon the float of each piston during nearly three-quarters of the revolution; but as the ports 72 and 74 in the auxiliary valves and openings *h* in the sleeves are only about one-fourth of the circumference of said valves and sleeves steam will enter each cylinder during only approximately one-fourth of the revolution of the cylinder and that during the remaining portion of the revolution until the exhaust commences the steam will be acting expansively. The left side of Fig. 7 shows the position of a sleeve when the engine is in use and also a position of the auxiliary valve relatively thereto while a cylinder is taking steam, and Fig. 9 shows the same position of the sleeve and a position of the auxiliary valve when the corresponding cyl-

inder is not taking steam. It will be obvious, therefore, that the length of the periods during which a cylinder is taking steam and is not taking steam is determined by the size of openings *h* and *k*, respectively, in the sleeve. While port 72, for example, registers with opening *k* no steam can pass into the cylinder owing to the solid metal *g* of the sleeve which bounds the opening. The instant, however, that port 72 passes a strip of the solid metal of the sleeve—for example, at the left in Fig. 7—steam will pass through opening *h* in the sleeve and thence through port 73 into the cylinder, steam continuing to pass through said port and opening into the cylinder until port 72 passes wholly out of alignment with opening *h*—for example, as in Fig. 9, which shows the position of the auxiliary valve relatively to the openings in the sleeve at the middle of the period during which the corresponding cylinder is not taking steam. While the exact size of the openings *k* in the sleeves is of no special importance, it will be noted that said openings are made large enough to insure a continuous and perfect exhaust through an opening *k* in each sleeve from either of the cylinders while said cylinder is taking steam through the other sleeve and also while steam is acting expansively in said cylinder. In other words, the exhaust is always free while there is any steam in the cylinder. This will be apparent from the right side of Fig. 7, it being obvious that steam is free to pass from opening *k* in the sleeve through said port 72 into auxiliary valve 47 and thence to the exhaust all of the time except the brief period during which solid metal on opposite sides of port 72 in the auxiliary valve registers with the solid metal *g* on opposite sides of said opening *k*. During this brief period of time there can be no exhaust from the corresponding cylinder, which is wholly unimportant, however, for the reason that during a longer period of time that begins before the exhaust is closed and continues after the exhaust is open again no steam can enter the cylinder, as it cannot pass the walls of opening *k* in the sleeve, as will be readily understood from the position of the parts illustrated in Fig. 9.

I wish it distinctly understood that I do not limit the use of my novel engine to steam or to any special motive power. So far as I am aware, the principle of this engine is radically new. For convenience in description I have spoken of steam as the motive power. It will be obvious, however, that the principle of this invention is adapted to widely-variant uses, as in stationary and marine engines generally and in pumps, and, furthermore, that the use of gas or water as a motive power is wholly within the scope of my invention. I have shown the auxiliary chambers as located above the cylinders. Any other arrangement may, however, be adopted, if preferred. For example, the auxiliary chambers may be located under the cylinders or at

either side of them, as may be found most convenient in designing engines for special uses.

Having thus described my invention, I claim—

1. A rotary engine comprising a plurality of cylinders in alinement with each other, rotary pistons therein, a main valve, and an auxiliary valve comprising a hollow rotary member having independent ports for the cylinders.

2. A rotary engine comprising a plurality of cylinders in alinement with each other, rotary pistons therein, a main valve, and auxiliary valves each comprising a hollow rotary member having independent ports for the cylinders, each of said auxiliary valves being adapted to control either the supply or the exhaust.

3. A rotary engine comprising a plurality of cylinders in alinement with each other, rotary pistons therein, a main valve, and auxiliary valves comprising hollow rotary members corresponding in length with the length of the space occupied by the cylinders and having independent ports for the cylinders.

4. A rotary engine comprising a plurality of cylinders in alinement with each other, rotary pistons therein, a main valve, and auxiliary valves comprising hollow rotary members corresponding in length with the length of the space occupied by the cylinders and having independent ports for the cylinders, each port being the full length of its respective cylinder.

5. A rotary engine comprising a plurality of cylinders in alinement with each other, rotary pistons therein, a main valve, and auxiliary valves comprising hollow rotary members having independent ports for the cylinders, and oscillatory sleeves outside of the valve members, said sleeves being adapted to change each valve member from supply to exhaust or from exhaust to supply.

6. A rotary engine comprising a plurality of cylinders in alinement with each other, rotary pistons therein, a main valve, and auxiliary valves comprising hollow rotary members having independent ports for the cylinders, oscillatory sleeves outside of the valve members, said sleeves being adapted to change each valve member from supply to exhaust or from exhaust to supply, and reversing-gear for oscillating said sleeves.

7. A rotary engine comprising a plurality of cylinders in alinement with each other, rotary pistons therein, a main valve, and auxiliary valves comprising hollow rotary members having independent ports for the cylinders, sleeves 49 and 50 surrounding said valve members, shafts 55 and 56 for operating said sleeves, and means whereby said shafts and the sleeves and the main valve may be oscillated in unison.

8. A rotary engine comprising a plurality of

cylinders in alinement with each other, rotary pistons therein, a main valve, and auxiliary valves comprising hollow rotary members having independent ports for the cylinders, sleeves 49 and 50 surrounding said valve members, shafts 55 and 56 for operating said sleeves, and means whereby said shafts and the sleeves and the main valve may be oscillated in unison, said means comprising pinions on the ends of the sleeve-shafts, a lever for operating the main valve, and toothed racks carried by said lever and engaging said pinions.

9. A rotary engine comprising a plurality of cylinders in alinement with each other, rotary pistons therein, a main valve, and auxiliary valves comprising hollow rotary members having independent ports for the cylinders, sleeves 49 and 50 surrounding said valve members, shafts 55 and 56 for operating said sleeves, and means whereby said shafts and the sleeves and the main valve may be oscillated in unison, said means comprising pinions on the ends of the sleeve-shafts, a lever for operating the main valve, and toothed racks carried by said lever and engaging said pinions, one end of said lever having three notches 60, a spring-catch being provided to engage either of said notches to hold the lever and the main valve and the auxiliary-valve sleeves in either one of three positions.

10. The auxiliary valve 47 consisting of a cylinder closed at each end and having a circumferential external groove near one end, a plurality of holes leading from said groove to the interior of the valve, and a plurality of elongated ports at different distances from said grooved end.

11. The auxiliary valve 47 consisting of a cylinder closed at each end and having a circumferential external groove near one end, a plurality of holes leading from said groove to the interior of the valve, and a plurality of elongated ports at different distances from said grooved end, said ports being formed out of alinement with each other.

12. In an engine of the character described the combination with rotary pistons having radial floats diametrically opposite to each other and auxiliary disks of uniform diameter with the pistons and provided with recesses which give clearance to the floats, of a main valve, auxiliary valves having receiving holes and ports opposite to each other whereby steam is supplied to the cylinders alternately and reversing-sleeves which enclose the auxiliary valves and are operated in unison with the main valve.

In testimony whereof I affix my signature in presence of two witnesses.

HEZEKIAH A. BENSON.
